CLAIM

The ornamental design for a front grille for a vehicle, as shown and described.

DESCRIPTION

FIG. 1 is a front left elevated perspective view of a front grille for a vehicle.

FIG. 2 is a front left perspective view thereof.

FIG. 3 is a rear right elevated perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is another front view of the front grille for a vehicle shown mounted on a vehicle.

The broken line showing is for the purpose of illustrating environmental structure and forms no part of the claimed design.
